UNITED STATES PATENT OFFICE.

CHARLES P. HULBERT, OF CHICAGO, ILLINOIS, ASSIGNOR TO HULBERT & DORSEY, A FIRM COMPOSED OF CHARLES P. HULBERT AND JOHN T. DORSEY, OF CHICAGO, ILLINOIS.

PLUMBING-FITTING.

1,093,626.

Specification of Letters Patent. Patented Apr. 21, 1914.

Application filed February 13, 1914. Serial No. 818,471.

To all whom it may concern:

- Be it known that I, CHARLES P. HULBERT, a citizen of the United States, and resident of Chicago, county of Cook, and State of Illinois, have invented certain new and useful Improvements in Plumbing-Fittings, of which the following is a specification, and which are illustrated in the accompanying drawings, forming a part thereof.
- 10 The invention relates to plumbing and more particularly to a fitting adapted to be interposed in an inclined drain at any one of a plurality of different positions and to provide an inlet opening to such drain at 15 the same elevation in each of said positions.
- In buildings having solid floors, as those constructed from reinforced concrete, plumbing fixtures which are so constructed as to discharge through the wall are desirably employed. When a plurality of such fixtures, as a row of toilet closets are provided, these preferably all discharge into a common drain. To provide suitable drainage the drain pipe must be inclined, whereas the 25 toilet fixtures are preferably all located at the same level. Heretofore the connection of such fixtures to a common inclined drain has required the use of a fitting of different form in connection with each fixture.
- 30 The present invention accordingly contemplates a fitting which may be modified to provide an inlet opening at a predetermined level irrespective of the level of the drain pipe at the particular location where the 35 connection is to be made.

The object of the invention is to facilitate the connection of so called wall closets and other forms of toilets which discharge through the wall at the rear to a common 40 drain.

In the accompanying drawings:—Figure 1 is a front elevation showing an inclined drain equipped with a plurality of fittings of the form provided by the invention, the 45 toilet closets to be connected with such fittings being shown in dotted lines and a detail of the floor of the building being shown in section; Fig. 2 is a detail front elevation of the fitting; Fig. 3 is a detail sectional view taken on the line 3—3 of Fig. 1; Fig. 50 Fig. 4 is a plan view showing a form of fitting which may be employed for the connection of two oppositely facing toilets to a common drain located in the intervening wall

space, and Fig. 5 is a detail sectional view 55 taken on the line 5—5 of Fig. 4.

The fitting illustrated in the drawings is more particularly intended for use in connection with the installation of wrought iron drainage systems. When so used, a 60 drain 24, which is preferably common to a plurality of toilet closets, as 10, 11 and 12 is formed by the connection of an equal number of fittings, generally designated 13, and intervening sections, as 14 and 15, of 65 wrought iron pipe to separate the said fittings in accordance with the spacing of the closets.

Each of the fittings 13 conveniently comprises a substantially cylindrical body portion 16 having internally threaded hubs 17, 18 at its opposite ends. Intermediate the ends of the cylindrical body portion 16 and extending laterally outward therefrom is a hollow extension 19, the chamber, as 20, of 70 which forms a well which is in communication with the bore of the cylindrical body portion 16. Preferably the extension 19 has a horizontal floor 21 and an outwardly and upwardly inclined top wall 22. Most desirably the floor 21 of the extension 19 is on a level with the bottom wall of the cylindrical body portion 16 of the fitting and the top wall of the extension extends upwardly from the level of the top wall of the body portion 16. By this means, the front wall, as 23 of the extension is of a greater height than width and extends from substantially the level of the under side of the cylindrical body of the fitting to an elevation 75 considerably above that of the upper side of the body portion of the fitting. In the original construction of the fitting the front wall 23 of the extension 19 is desirably closed.

When a plurality of the fittings, 13, are to be employed for the connection of a plurality of closets, as 10, 11 and 12, to a common drain 24, the front wall 23, of the extension 19 of each fitting is drilled 80 to provide an opening 25 therein for the connection of the closet to the fitting at a fixed distance from the floor, as 26. As the pitch of the drain 24 serves to locate the several fittings 13 at different elevations, the opening 25 in the front wall 23 of the several fittings will be located at different places, the said opening in the fitting which

is located in a higher part of the drain being positioned lower down upon the fitting than are the said openings of the fittings which are located at a lower part of the drain. The 5 toilet closets, as 10, 11 and 12 may be connected with the respective fittings 13 in any convenient manner, as for example in the manner illustrated in Fig. 3. In this figure the rear wall of one of the closets, as 10, 10 is represented at 27, the discharge opening in said wall being shown at 28. In this instance the closet 10 is located against an upright wall or panel represented by dotted lines at 29 and the fitting 13 is located in 15 rear of this panel. The front wall 23 of the lateral extension 19 of the fitting have been drilled at the proper elevation to provide an opening 25 therein which is upon the same level as the discharge opening 28 20 in the rear wall of the closet 10, a threaded nipple 30 is screwed into the opening 25 and extends through the panel 29. A flanged collar 31 is then screwed upon the front end of the nipple 30 and secured against the 25 rear wall of the closet 10 about the discharge opening 28 by bolts, as 32. A more substantial support for the closet may be obtained by mounting a collar 33 upon the nipple 30 between the front wall 23 of the 30 fitting 13 and the collar 31, and by the extension of the bracket arms or braces, as 34, from the collar 33 to the rear wall 27 of the closet above the discharge opening 28. Each of the closets, as 10, 11 and 12 may 35 be secured to the corresponding fitting 13 in the same manner as is shown for the closet 10, the different location of the opening 25 in each fitting serving to permit of all of the closets to be positioned at the same distance from the floor 26 notwithstanding the pitch or inclination of the common drain 24. Usually each of the fittings 13, will 40 be provided with an opening 35 at the upper side of its cylindrical body portion for the connection therewith of the usual vent, as 36. 45

When closets which are located at the opposite sides of a wall or partition are to be connected with a common drain, a fitting of the form shown in Figs. 4 and 5 will desirably be used. This fitting may take the 50 general form of a so-called long sweep double 90 degree Y, having a central cylind-

rical body portion, as indicated at 37, and the two oppositely facing lateral branches, as 38 and 39. The two branches 38, 39 are 55 each preferably made vertically flaring adjacent their outer ends (Fig. 5) and in the original construction of the fitting, these branches will preferably be closed at their outer ends. When a plurality of the fittings 60 are to be mounted in an inclined drain (not shown) the closed ends of the lateral branches 38 and 39 of the several fittings will be so drilled as to provide inlet openings, as 40, all of which will be located at the 65 same elevation. By means of the invention fittings of a uniform design will serve for the connection of a plurality of plumbing fixtures, all located at the same elevation, with a common drain. The use of a fitting 70 of special form or the construction of built up elbow branches to different heights at the several places where fixtures are located is accordingly avoided.

I claim as my invention, —

1. A drain for closets and the like comprising, in combination, a plurality of inclined pipe sections located in alinement and a plurality of integral fittings each comprising a tubular part interposed between and connecting adjacent pipe sections and a vertically extended lateral receiving chamber communicating with the bore of the said tubular part and having an upright end wall, the said end walls of all 80 of the said fittings being drilled at the same elevation for connection with the horizontally directed outlets of wall closets and the like.

2. A fitting for inclined drains comprising 90 in combination, a cylindrical tubular body portion having its opposite ends adapted for connection with sections of the drain pipe and a pair of oppositely facing vertically extended lateral arms each having an 95 end wall adapted to be drilled at any one of a plurality of different elevations for connection with the horizontally directed outlet of a wall closet.

CHARLES P. HULBERT.
